UNITED STATES PATENT OFFICE

2,650,639

MACHINE FOR STRAIGHTENING AND POLISHING METAL ROUND SECTION BARS OR TUBES

Ronald Hampton, Wightwick, near Wolverhampton, England, assignor to The Union Steel & Manufacturing Company Limited, Wolverhampton, Staffordshire, England

Application November 30, 1951, Serial No. 259,025
In Great Britain December 7, 1950

4 Claims. (Cl. 153—108)

1

The invention relates to machines for straightening and polishing round metal bars or tubes usually of ferrous metal by a process known as "reeling." In a reeling machine of known type for carrying out this process two chilled cast iron rolls, one of which is of concave form and the other of convex form are mounted longitudinally side-by-side but without touching. They are so mounted in bearings of the machine that their axes are inclined to a common plane, the inclination of the one being the opposite way to that of the other. The rolls are rotated in the same direction and the work is presented to the rolls longitudinally and is held up to the rolls by a longitudinal straight bearer, the distance apart of the rolls being such that the work always remains below the said common plane. Means are provided for adjusting the bearer towards and from the rolls and the distance apart of the rolls is adjusted, in either case, to suit the diameter of the work. The bearer is usually of metal or hard wood. The work is so held by the bearer that it bears against the middle part of the convex roll and against the two ends of the concave roll.

The effect of the reeling process is that the work is continuously rotated by the rolls and bent and rubbed by them and also rubbed by the bearer. The combined effect is to cause the work to be fed along the bearer and to suffer a continuous bending strain. As a result the work leaves the rolls straight and polished.

A disadvantage of the process is that it is relatively slow and the object of this invention is to increase the amount of work which can be processed per minute.

According to this invention a second longitudinal bearer is provided and is located opposite the existing bearer, that is to say on the other side of the said common plane, so that two bars or tubes can be processed at the same time.

The rolls may be disposed side-by-side in plan view of the machine with the bearers located one below the rolls and the other above them, or the rolls may be disposed one above the other in the machine, with the two bearers located one at each side.

An embodiment of the invention will now be described with reference to the accompanying drawings, in which:

Fig. 1 is a fragmentary side elevation of a reeling machine.

Fig. 2 is a sectional view on the line 2, 2, of Fig. 1.

Referring to the drawings, the reeling machine comprises end frames 10 in which are jour-

2

nalled two chilled cast iron rolls 11 and 12 respectively, the roll 11 being of convex form and mounted in bearings 13 in said end frames, whilst the roll 12 is of concave form and is similarly mounted. Both rolls are driven in rotation in the same direction, as through gear trains (not shown) enclosed by guards 14, and are disposed in side-by-side relationship in plan view with their respective axes oppositely inclined to a common horizontal plane indicated by the line A, A in Fig. 1.

A length of round bar 15 is presented to the rolls 11 and 12 longitudinally and is held up to the rolls by a longitudinal straight bearer 16, the distance apart of the rolls being such that the bar 15 always remains below the common plane A, A. The bearer 16 is carried by screws 17 which pass through tapped holes in a supporting strut 18, and by turning the screws 17 simultaneously the bearer 16 can be adjusted bodily towards and away from the rolls to suit the diameter of the work, locking nuts 19 being provided for setting the position of the bearer after adjustment. The concave roll 12 is mounted in laterally slidable bearing blocks, one of which is seen at 20 in Fig. 2, and a mechanism (not shown) is provided for moving these blocks and with them the roll 12 towards or away from the non-adjustable convex roll 11, this adjustment being made along with adjustment of the bearer 16 to suit the diameter of the work.

The bearer 16 may be of metal or hard wood and the bar 15 is so held by the bearer 16 that it bears against the middle part of the convex roll 11 and against the two ends of the concave roll 12 the operation of this "reeling" process being that the work is continuously rotated by the rolls and bent and rubbed by them and the bearer, being fed along the bearer due to the inclination of the roll axes and suffering a continuous bending strain, finally leaving the rolls straight and polished.

A second bearer 21 is provided and is located opposite the bearer 16, that is to say on the other side of the plane A, A, this second bearer 21 being adjustably mounted in like manner to the bearer 16 and carried by screws 22 which pass through tapped holes in a supporting strut 23, so that by turning the screws 22 simultaneously the bearer 21 can be adjusted towards and away from the rolls to suit the diameter of a second length of round bar 24 which is processed by the machine at the same time as the bar 15, but on the opposite side of the rolls and the plane A, A. Locking nuts 25 are provided for setting the

position of the bearer 21 after adjustment thereof.

The two bars or tubes passing through the machine at the same time may be of the same or of different diameters within reasonable limits by appropriate adjustment of the bearers 16 and 21.

It will be seen that the provision of first and second bearers in cooperation with the rolls, provides two passes for the bars or tubes and thus doubles the length of work which can be processed by the reeling machine per minute.

Whilst in the reeling machine above described only the concave roll is adjustable, it will be understood that either or both rolls may be adjustable if desired.

Having fully described my invention, what I claim and desire to secure by Letters Patent is:

1. In a reeling machine the combination of two rolls of concave and convex form respectively mounted in longitudinal side-by-side relationship with their axes oppositely inclined to a common plane, a first longitudinally disposed bearer mounted at one side of said common plane and spaced from said plane a sufficient distance to define with said rolls, a first pass spaced from said plane for receiving a first work piece, and a second longitudinally disposed bearer mounted at the other side of said common plane and spaced from said plane a sufficient distance to define with said rolls, a second pass spaced from said plane for receiving a second work piece.

2. A reeling machine as set forth in claim 1 wherein both bearers extend throughout the lengths of said rolls.

3. A reeling machine as set forth in claim 2 wherein both bearers are longitudinally straight.

4. In a reeling machine, the combination of a pair of rolls of concave and convex form respectively positioned in longitudinal side-by-side relationship with their axes relatively inclined oppositely with respect to a common plane, the peripheries of said rolls being spaced apart throughout the lengths of the rolls, and a pair of spaced-apart work receiving passes respectively positioned on opposite sides of said common plane, each pass comprising three longitudinally extending lines of contact for the work, two of said lines comprising adjacent surfaces of said rolls, a first longitudinally extending bearer spaced from and positioned at one side of said common plane and forming the third line of contact for the work positioned in one pass, and a second longitudinally extending bearer spaced from and positioned on the opposite side of said common plane and forming the third line of contact for the work positioned in the other pass.

RONALD HAMPTON.
